[57] CLAIM

The ornamental design for a combined cooking and serving bowl, as shown.

DESCRIPTION

FIG. 1 is a top perspective view of a combined cooking and serving bowl showing my new design;

FIG. 2 is a top plan view thereof to an enlarged scale;
FIG. 3 is an elevational view as seen from the right or left side of FIG. 2; and

FIG. 4 is a top plan view of FIG. 2, the cover having been omitted for convenience of illustration.
